DESIGN FOR A TEXTILE FABRIC

Ira Strauss, New York, N. Y.

Application February 18, 1938, Serial No. 75,250

Term of patent 3½ years

To all whom it may concern:

Be it known that I, Ira Strauss, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

The top of the fabric is shown on the left hand side of the disclosure.

I claim:

The ornamental design for a textile fabric, substantially as shown, and described.

IR A STRAUSS.
